[57] CLAIM

The ornamental design for a finial for drapery curtain rod, as shown and described.

DESCRIPTION

FIG. 1 is a perspective view of a finial for a drapery curtain rod showing my new design;

FIG. 2 is an end elevational view thereof;

FIG. 3 is an end elevational view of the other end thereof; and,

FIG. 4 is a side elevational view thereof, the other side being a mirror image.

The broken line showing of the drapery curtain rod in FIG. 1 is for illustrative purposes only and forms no part of the claimed design.
